The ornamental design for an operating console for a printing machine, as shown and described.

DESCRIPTION

FIG. 1 is a top, right side perspective view of an operating console for a printing machine showing my new design; FIG. 2 is a top, right side perspective view thereof, viewed from a steeper angle;

FIG. 3 is a right side elevational view thereof;

FIG. 4 is a left side elevational view thereof; and,

FIG. 5 is a front elevational view thereof.

The broken lines illustrate portions of the operating console for a printing machine which form no part of the claimed design.
